UNITED STATES PATENT OFFICE.

HARRY VAUGHAN RUDSTON READ, OF LONDON, AND ROBERT HUNTER CAMPBELL, OF EDMONTON, ENGLAND.

FIRE-EXTINGUISHER APPARATUS.

940,614.

Specification of Letters Patent. Patented Nov. 16, 1909.

Application filed March 29, 1909. Serial No. 486,556.

To all whom it may concern:

Be it known that we, HARRY VAUGHAN RUDSTON READ, a subject of the King of Great Britain and Ireland, of 1 Broad Street 5 avenue, in the city of London, England, and ROBERT HUNTER CAMPBELL, a subject of the King of Great Britain and Ireland, of Angel Road, Edmonton, in the county of Middlesex, England, have invented new and 10 useful Improvements in Fire-Extinguisher Apparatus, of which the following is a specification.

This invention relates to fire extinguishers and other liquid-ejection apparatus wherein 15 gas is released from containers of compressed or liquefied gas by piercing the closure of the said containers.

It is the object of our invention to provide a very efficient and convenient construction 20 of such apparatus which is not liable to get out of order and which is very certain in action.

We will presume, for the purposes of description, that the improvements are applied 25 to fire extinguishers, to which they are especially applicable, and, from this description, the application of the invention to other analogous apparatus will also be understood.

30 In the accompanying drawings, Figure 1 is a side elevation, Fig. 2 is a plan, and Fig. 3 is a vertical section (with part broken away) of a fire-extinguisher constructed in accordance with this invention. Fig. 4 represents a modification, and Fig. 5 shows 35 separately, in perspective, the device which acts as a seal.

The body-part, or liquid-containing vessel 1 of the extinguisher is provided with a 40 tubular connecting piece 2 projecting some distance into the body-part and secured in an opening in the body 1 by a flange 3 on the said connecting piece 2, being held between the interior part of the said body-part 1 around the said opening and a ring of solder 4. The externally projecting end of the said connecting piece 2 is screw threaded and its interior is provided with a shoulder 5, on which the flange 6 of this 45 container 7 is supported, the said flange 6 being held between the said shoulder 5 and the lower end of a cylindrical piece 8, with 50 a closed top 9, which piece 8 is a sliding fit in the connecting piece 2.

The cylindrical cap 10 is provided in its 55 interior with a screw thread adapted to be screwed onto the projecting end of the said connecting piece 2, and the said cap 10 is provided with a washer 11 to make a gas-tight joint between itself and the upper end 60 of the connecting piece 2. The said cap 10 has formed in one with it a stuffing box 13, adapted to have the gland 12 screwed into it. The stem 16 is screwed, or otherwise fixed, at one end into a plunger 17 capable of sliding 65 in the cylindrical piece 8, the other end of the said stem 16 being adapted to be screwed into a piece 15 which has a hollow 14 in it which can slide over the stuffing box 13, the said end piece 15 having preferably a 70 stand, or tripod, at its outer end, as shown. The inner end of the said stem 16 carries the piercer proper 18 made of any suitable hard and non-corrosive metal. A spring 19 is placed between the gland 12 and the outside 75 of the hollow 14 in the end-piece 15, this spring 19 being sufficiently strong, not only to carry the weight of the charged extinguisher, when it is in an inverted position and resting on the end piece 15, but also to 80 extract the piercer 18 after it has pierced the closure of the container 7, so as to allow, with certainty, free passage for the gas from the container through the pierced opening, the gas passing into the interior of the part 85 1 by openings 20 and 21 made respectively in the cylindrical piece 8 and the connecting piece 2, the said cylindrical piece 8 having in it a circular groove 22 to give communication 90 between the openings 20 and 21 for the passage of the gas into the body-part 1 of the extinguisher, so that the said openings 20 and 21 need not be in line with each other. Between the underside of the end-piece 15 and the cap 10 is a piece 23 (shown 95 separately in Fig. 5) made of a substance which will easily break and consisting of an upright piece joining upper and lower side pieces shaped to embrace the stuffing box 13, the ends of this piece 23, when it is in place, 100 being sealed for instance by a seal 24 sealing a wire secured to each end of the said piece 23, so that the piece 23 cannot be removed without breaking the seal 24. When

the capsule 7 is opened by the piercer 18, the piece 23 is fractured, and by its condition it can readily be seen whether the capsule has been opened or whether it is in working order.

Attached to the connecting piece 2 is a wire 32, preferably coiled as shown, by which the lever to which water may be charged into the body part 1 can be seen as it is necessary to leave a space above the liquid sufficient to prevent a dangerous pressure when the gas is released and to allow the entering gas to efficiently apply the pressure for ejecting the water.

15 The outlet for water and gas from the apparatus is at 25, and is preferably guided by a perforated or reticulated shield 26, and is shown as being provided with a hose 27 having a nozzle 28 and also, if required, a tap 29. The hose is preferably made light and strengthened by wire armoring.

In the modification shown in Fig. 4, the head-piece 15 is replaced by a simple knob 30 to take the bearing of the spring 19 and 25 on the shoulder 5 of the connecting piece 2 is supported a holder 33 for the container 7 when it is not provided with a flange 6 capable of being supported on a shoulder, as in Fig. 3. A wire, similar to that shown at 30 32 in Fig. 3, can be attached to the connecting piece 2 for the purpose of indicating the level to which water may be charged into the body part 1. The parts which correspond with those shown in the other figures are 35 marked with the same reference numerals. The piercing can be effected by reversing the extinguisher and striking its head-piece 15 or knob 30 on the floor, or other convenient place, for which purpose we have shown 40 handles 31 both above and below. The head piece 15, or knob 30, is thus forced inward and the sealing piece 23 is fractured and the piercer 18 penetrates the closure of the container 7 and then the spring 19 withdraws 45 the piercer 18, and the container 7 cannot

follow it as it is held in position by the cylindrical piece 8 which is in turn held in place by the washer 11 abutting against the cap 10.

We have shown the extinguisher as not 50 having a siphon tube for the outlet of the water and gas, but, if desired, a siphon tube can be used, as indicated in dotted lines in Fig. 3, when the piercing can be effected by striking the head piece or knob with a hammer or other instrument, or by holding it in a horizontal position and striking it against a wall, for instance. Although we have mentioned water, of course any suitable liquid or solution can be charged into the extinguisher or the like.

We claim as our invention—

In fire extinguishers and other liquid ejection apparatus, into which gas is liberated from a container of compressed or liquefied 65 gas, the combination with the body part of the apparatus of a cylindrical connecting piece provided with a shoulder to support the container, a cylindrical piece capable of being inserted in the said connecting piece 70 to hold the container in position against the shoulder, a cap secured to the said connecting piece and provided with a stuffing box, a stem carrying a piercer and passing through the stuffing box, a plunger movable 75 in the cylindrical piece and connected to one end of the stem and an end piece connected to the other end of the stem and adapted to be projected outward by a spring together with sealed means for preventing 80 accidental actuation of said plunger, all substantially as hereinbefore described.

In testimony whereof we have signed our names to this specification in the presence of two subscribing witnesses.

HARRY VAUGHAN RUDSTON READ.
ROBERT HUNTER CAMPBELL.
